APPARATUS FOR LAUNCHING A LIFEBOAT

Henri Fernand Petit-Colas, Gournay-en-Caux
par Harfleur, and Louis Jules Besnier,
Havre, France

Application November 30, 1932, Serial No.
645,136, and in France December 4, 1931

3 Claims. (Cl. 9—22)

It is known that the launching and raising of ships' lifeboats is generally effected by man power by traction or release of the fall or rope of the tackle for the davit. Now, this operation is long and tedious. It has, in addition the inconvenience of irregularity in the raising or lowering and often of a dangerous inclination of the boats due to the want of uniformity of the release or the pull on pulley blocks of the same vessel.

Finally, the attachment of the pulley blocks to the boats does not afford absolute security and it has been found that in the haste made in the operation at the time of a disaster this attachment may not have been verified so causing the drop of one end of the vessel.

The present invention has for object to overcome these various inconveniences and to render the operation of launching or raising the life-boats of ships very easy and very certain.

For this purpose it provides for the fitting to the boats themselves of an apparatus which will permit a rapid operation and which is also gentle and precise giving an absolute security all the time.

This apparatus consists first of all of a double winch secured to the boat and comprising two identical drums connected inseparably together by two identical gears. Said drums are actuated either by hand or by any suitable motor through the intermediary of the said gear and of a demultiplying arrangement consisting of an endless screw or pinion wheels.

Said apparatus is completed by clutch and brake mechanism operated manually or automatically or both ways, which provides great smoothness and great reliability in movement.

It is thus that in a form of construction which has been thought preferable, the apparatus comprises means for the automatic adjustment of the speed of lowering limiting the latter to a predetermined value even if there is lack of inspection during the operation.

Moreover, in this form of construction the apparatus likewise comprises braking means operated manually which permits of reducing the speed of the boat and to retain the latter at a short distance from the hull and in this way give great precision in the handling.

Finally, the invention provides for an arrangement for instantaneously fixing the cables on the drums or their rapid disengagement therefrom, the other extremity of the cables remaining constantly secured to the davits or cathead of the boat.

The invention will moreover be better understood from a perusal of the following description, reference being had to the accompanying drawings which show:

Figs. 1 and 2 the apparatus mounted on a lifeboat, in longitudinal section and in plan;

Fig. 3, a first form of construction of the apparatus seen in elevation;

Fig. 4, a section taken on the line 4—4 of Fig. 3;

Fig. 5, the same apparatus seen in plan view;

Fig. 6, the method of fixing the cables to the drums;

Fig. 7, a second form of construction of the apparatus seen in section taken on the line 7—7 of Fig. 8;

Fig. 8, a section taken in a horizontal plane passing through the line 8—8 of Figure 7;

Fig. 9, a part section taken on the line 9—9 of Figure 7.

The apparatus realized according to the invention comprises essentially a frame 1 secured to the middle of the boat and carrying two drums 2 connected by two similar or equal gear 3 (Figs. 1 and 2).

The drums 2 are preferably provided with grooves for guiding the cables 4. These latter are secured to the davits or catheads of the ship or to any other installation. After having passed through hawse holes 5 provided in the bridge work of the boat the cables pass over two pulleys 6 and each winds round a drum 2 after having been passed beneath it.

In the first form of construction, the frame consists of two symmetrical cheeks (Figs. 3 to 5) suitably braced, but this frame given simply by way of example, can be otherwise constructed.

The drums can be manually operated or driven by motor through a demultiplying speed gear. In the said construction (Fig. 3 to 5) this arrangement comprises first of all a wheel 7 with helicoidal teeth, fastened on the shaft or spindle of one of the drums and meshing with an endless screw 8 which is irreversible, keyed on the driving shaft 9 and actuated manually or mechanically.

The socket of a crank handle 10 which has lateral teeth or dogs 10_a and which in addition carries a tooth wheel 11 rigid therewith rotates and slides freely on shaft 9.

On the shaft 9 is also secured a toothed wheel 12 the hub of which is provided with teeth or dogs 12_a similar to the teeth or dogs 10_a of the crank handle socket and capable of coming into engagement therewith upon a sliding movement

towards the wheel 12 of said socket on the shaft 9.

The toothed wheel 12 is constantly in mesh with another toothed wheel 13 of larger diameter, fixed on a lay shaft 14 on which is keyed a toothed wheel 15 engaging or meshing with the wheel 11 of the socket of the crank handle when said socket slides on the shaft 9 towards the said wheel 15.

When in gear with the dogs 12a, the socket 10 of the crank handle 10 is directly united with the shaft 9 and the wheel 11 is disengaged from the wheel 15. This position is provided for the raising of the boat during which the movement of the crank handle must be transmitted more slowly to the screw 8.

On the contrary, in the opposite position, the socket of the crank handle 10 is intermeshed by the gear 11 with the shaft 14, thus forming a demultiplying speed gear which permits, at the lowering, to obtain an increased speed through the screw 8 with a restricted number of turns of the crank handle.

The method of fixing the cables 4 on the drums must allow of their easy separation from said drums. For this purpose, various arrangements can be adopted, but according to a construction considered preferable (Fig. 6) the end of each cable 4 is fitted with a sleeve 16. The latter penetrates into a sheath 17 lodged in the hub 2a of each drum 2. This sheath is provided internally with a certain number of spring blades 18 suitably elbowed to form resilient bosses preventing the sleeve 16 of the cable from coming out of the sheath unless a strong pull is exerted thereon. A determined number of spirals or turns of the cable around the drums must be allowed for the lowest position of the boat in order to permit of a direct pull on the cable and its sleeve 16 before the final stage of the launching operation.

Nevertheless, to abridge the rotation of the drums necessary for unwinding the excess of cable around them, a clutch device may be provided to permit of their rapid rotation.

In this way (Figs. 3 and 4) the hub of the drum 2 mounted on the same shaft as the toothed wheel 7 can be provided with teeth or dogs integral with a dog clutch 19 capable of engaging with the wheel 7 turning loosely or freely on the shaft of the drum.

A fork 20 is mounted on a shaft 21 which receives its movement from a clutch lever 22 protruding beyond the frame 1.

The operation of the apparatus is therefore as follows:

For launching the crank handle 10 is pulled towards the operator, the speed gear intervenes, the cables 4 unwind exactly the same amount during the rotation of the drums 2 which is even, and the boat is lowered. By acting on the crank handle the desired speed of lowering is obtained.

When the boat has reached the water, the drums are instantaneously released from the helicoidal wheel 7 by acting on the clutch lever 22. The cables unwind of their own free will, always evenly, and the boat becomes free of such cables without any particular operation for this purpose.

For the raising of the boat, the cables 4 hanging from the davits, are passed into the hawse holes 5 then over the pulleys 6 then the terminal sleeves 16 are engaged in the sheaths 17 of the drums. The crank handle 10 can be set into a speed of descent so as to wind up the slack nec-

essary for the cables then at a speed for the raising operation, that is to say in direct mesh with the shaft 9.

The endless screw 8 being irreversible, the crank handle 10 can be released at any moment 80 without danger.

The driving means for the drums may nevertheless receive modifications and instead of comprising an endless screw, could consist simply of a train of gear wheels provided with appropriate safety devices.

Thus for example in a further constructional form of the apparatus (Figs. 7 and 8) the two drums, integral with their two similar gears 3, are driven through the intermediary of a pinion wheel 7' engaging with one of the gears 3 and carried by an intermediate shaft 9a. On this shaft is secured a toothed wheel 12' meshing with a pinion wheel 13' of a second intermediate shaft 9b. This shaft carries a toothed wheel 15' fixed thereon, and meshing with a pinion wheel 11' provided on the driving shaft 9.

It will be seen that in this case the train of gear wheels is transformed into a speed reducing gear.

The shaft 9 is provided with crank handles 10 at each end but which are to be used only for the raising of the boat. To co-act with the irreversibility of the endless screw 8 and consequently with the sudden descent of the boat, 105 various devices for braking and safety may be provided.

In the form of construction illustrated, the motor shaft 9 is provided with a brake with shoes 23 (Figs. 7 and 9) operated by means of 110 a lever 24 protruding at the exterior of the frame 1, but this brake might equally well be in the form of a drum, or cable brake and so on.

Moreover, to automatically regulate the speed of the descent, it is possible to establish on the 115 driving shaft 9 or on one of the intermediate shafts 9b, for example, a centrifugal braking device 25 (Fig. 8) acting in a drum 26 integral with the frame and comprising masses or blades 120 braking the rotation of the said shaft all the more energetically as the speed becomes greater.

For the raising of the boat, the shaft 9 is operated by the crank handles 10 and to prevent any escape occurring, a safety device should 125 be fitted on the said shaft.

For this purpose, a ratchet 27 (Figs. 7 and 9) is arranged on the shaft 9 and a pawl 28 operated from the outside by a lever 29 can be arranged to prevent any backward return of the 130 crank handles. For the lowering operation the pawl 28 is reversed and held in such position by a stop 30 so as not to fall back onto the teeth of the ratchet 27.

The operation of the modified form of apparatus will be easily understood:

For the launching, it suffices to remove the pawl 28 for the boat to immediately commence to descend under the load and its own weight. The speed of descent is adjusted automatically 140 by the centrifugal braking mechanism 25.

At the moment when the boat comes near to the hull, it is then possible by acting on the lever 24 to brake the rotation of the shaft 9 which is very rapid and check the descending movement to the speed desired so as to bring the boat into the water with all the precision and the smoothness desired.

The hand brake 24 obviously allows of locking 150

or holding the shaft 9 as soon as it is considered desirable.

For the raising operation, the pawl 28 is placed in contact with the ratchet wheel 27 and then, by means of the crank handle 10 the shaft 9 is rotated and the boat is slowly and gently raised.

It is evident that in both forms of construction here above described it is possible to actuate the shaft 9 by means of a motor, through a pulley and a pinion wheel or any other appropriate manner with, in case of need, the interposition of a clutch mechanism.

It is likewise possible in both these cases to provide on the drums, two blades 31 (Figs. 3, 4, 5 and 7) mounted on an axle 32 and the tail ends of which are caused by a spring 33 to press on all the strands of the cable wound upon each of the drums 2.

The arrangements herein above described by way of simple explanation, remain nevertheless susceptible of receiving modifications in form and detail without thereby exceeding the spirit of the invention.

What we claim, is:

1. In an apparatus for launching and raising lifeboats on ships, two drums in the lifeboat, a gearing for said drums to ensure their synchronous rotation, two cables fixed with their one extremity to the vessel and with their other extremity to said drums, a terminal sleeve secured to the end of the said cables, a sheath

integral with the hub of each of said drums, and adapted to receive said sleeve, and blade springs in the said sheath to maintain the sleeve in said sheath but to permit of its release by simple pull thereon.

2. In an apparatus for launching and raising ships' lifeboats, two identical drums in the life-boat, a gearing to ensure their synchronous rotation, a driving shaft, means to actuate said driving shaft, directly or through the medium of a speed gear, two cables fixed with their one extremity to the ship and with their other extremity to said drums, and a centrifugal braking arrangement on one of the shafts of the speed gear for limiting the speed of descent automatically to a pre-determined value.

3. In an apparatus for launching and raising ships' lifeboats, two identical drums in the life-boat, a gearing to ensure their synchronous rotation, a driving shaft, a speed gear, means to actuate said driving shaft either directly or through the medium of said speed gear, two cables fixed with their one extremity to the ship and with their other extremity to said drums, a brake to limit the speed of the said driving shaft at the lowering of the boat, and a ratchet wheel fast on the driving shaft, to prevent an unintentional descent upon the rasing of the life-boat.
